United States Patent

Des. 240,459
Patented July 6, 1976

240,459

CONTROL UNIT WITH PRINTER

Ronald I. Conway, Port Ewen, John J. Natale, Woodstock,
and John V. Straub, Poughkeepsie, N.Y., assignees to
International Business Machines Corp., Armonk, N.Y.

Filed Aug. 29, 1974, Ser. No. 561,737

Term of patent 14 years

Int. Cl. D16—63

U.S. Cl. D16—30

FIG. 1

FIG. 2

FIG. 3

FIG. 1 is a top front perspective view of a control unit with printer showing our new design;

FIG. 2 is a top, left, and front perspective view thereof; and

FIG. 3 is a top, right, and rear perspective view thereof.

We claim:

The ornamental design for a control unit with printer, substantially as shown.
